Primary Examiner — Philip S. Hyder*Assistant Examiner* — Darlington Ly(74) *Attorney, Agent, or Firm* — Christensen O'Connor Johnson Kindness PLLC**CLAIM**

The ornamental design for a center chassis fairing cap, as shown and described.

DESCRIPTION

FIG. 1 is a perspective view of a front chassis fairing cap according to our new design;

FIG. 2 is a front view of the center chassis fairing cap of FIG. 1;

FIG. 3 is a top view of the center chassis fairing cap of FIG. 1; FIG. 4 is a bottom view of the center chassis fairing cap of FIG. 1; and,

FIG. 5 is a left side view of the center chassis fairing cap of FIG. 1.

FIGS. 1-5 illustrate a first embodiment of our novel design suitable for use on the left side of a vehicle. Our novel design also includes a second embodiment suitable for use on the right side of a vehicle, which is mirror symmetrical to FIGS. 1-5 and therefore not separately illustrated.

The broken lines shown in the drawings illustrate portions of the center chassis fairing cap that forms no part of claimed design.
